UNIT FOR HANGING AND PROTECTING GARMENTS

Filed Jan. 23, 1946

UNITED STATES PATENT OFFICE

2,473,902

UNIT FOR HANGING AND PROTECTING
A GARMENT

Charles E. Prahman, Cincinnati, Ohio

Application January 23, 1946, Serial No. 642,841

5 Claims. (Cl. 223—98)

1

The present invention relates to units for use in hanging and protecting garments.

In displaying and merchandising a garment it has heretofore been customary to utilize a conventional or standard hook equipped hanger and in addition a shoulder protector of the type that comprises coextensive front and rear panels which are formed of flexible material such as Pliofilm or cellophane and have the side margins thereof and the outer portions of their upper margins connected together by stitching in order that the protector as a whole is of unitary character, is open at the bottom and has a top opening adjacent the central portions of the upper margins of the two panels. In utilizing a unit in the form of a hanger and a shoulder protector the hanger is first applied to the shoulder portion of the garment. Thereafter the shoulder protector is sleeved or shifted over the shoulder portion of the hanger supported garment and is manipulated so that the hook of the hanger extends through the top opening between the stitched together outer portions of the upper margins of the front and rear panels of the protector. After so manipulating the protector the hook of the hanger is applied to a horizontal rod in order to support in a suspended fashion the garment to which the hanger and protector are applied. When it is desired to display or use the garment the hanger and protector are first removed from the rod by unhooking the hook of the hanger. Thereafter the protector is removed from the shoulder portion of the garment on the hanger by shifting it upwards while at the same time guiding the hook of the hanger through the top opening in the protector. In practice it has been found that a unit in the form of a conventional or standard hook equipped hanger and a shoulder protector of the aforementioned type has but a comparatively short life and is quite difficult to handle. The short life of the unit is directly attributable to the fact that repeated insertion and withdrawal of the hook of the hanger with respect to the top opening in the shoulder protector results in rupture or tearing of the front and rear panels of the protector. The necessity of withdrawing the hanger from the rod and removing the shoulder protector from the hanger supported shoulder portion of the garment each time it is desired to display or use the garment makes use of the unit both difficult and tedious.

The primary object of this invention is to provide a hanger and protector unit which is an improvement upon, and eliminates the disadvantages of, previously designed and utilized units

2

and is characterized by the fact that it comprises in addition to the conventional hook equipped hanger and the shoulder protector, a main or primary hook equipped hanger which is adapted normally to remain in connected relation with the shoulder protector and to hold the protector at all times in suspended relation with respect to the horizontal rod by which the unit is supported, and has means whereby the conventional hanger may be detachably suspended from it. By employing the primary hook equipped hanger it is only necessary in connection with use of the unit to detach the conventional hanger from the primary hanger when it is desired to display or use the garment on the conventional hanger. In the present unit the conventional hanger becomes and serves as an auxiliary hanger.

Another object of the invention is to provide a unit of the last mentioned type and character in which the primary hanger and the shoulder protector are provided with interlocking means whereby when the shoulder protector is in its operative or normal position with respect to the primary hanger it is held against upward displacement relatively thereto.

A still further object of the invention is to provide a hanger and protector unit which is generally of new and improved construction, may be manufactured at a comparatively low cost and may be handled or manipulated with facility.

Other objects of the invention and the various advantages and characteristics of the present hanger and protector unit will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a front elevation showing a hanger and protector unit embodying the invention in assembled form or relation and with a garment in place on the conventional hook equipped hanger constituting one of the component parts of the unit;

Figure 2 is a front view of the conventional hanger which is adapted to be applied to the shoulder portion of the garment to be supported by way of the unit and when in its normal or operative position is in suspended relation with respect to the primary hanger which normally re-

mains in connected relation with the shoulder protector;

Figure 3 is a vertical longitudinal section of the central portion of the primary hanger; and

Figure 4 is a vertical transverse section taken on the line 4—4 of Figure 3 and illustrating in detail the construction and design of the central portion of the primary hanger.

The unit which is shown in the drawing constitutes the preferred form or embodiment of the invention. It is primarily designed and adapted for use in hanging and protecting a garment and as its components or principal parts consists of a primary hanger 5, a shoulder protector 6 and a conventional or standard hanger 7.

The primary hanger 5 is adapted to be suspended from a horizontal hanger rod 8 in a closet or display cabinet and serves, as hereinafter described, as a supporting instrumentality for the shoulder protector 6 and the conventional or auxiliary hanger 7. It is of composite but unitary construction and comprises a central housing 9, an upstanding hook 10 and a pair of outwardly and oppositely extending arms 11. The housing 9 is preferably in the form of a one-piece sheet metal stamping and consists of a substantially semicircular front wall 12, a substantially semicircular rear wall 13 and an arcuate side wall 14 between the front and rear walls. As shown in the drawing the front and rear walls are disposed in spaced apart and parallel relation and are arranged so that the straight marginal portions thereof are at the bottom. The arcuate side wall 14 extends between and is formed integrally with the curved marginal portions of the front and rear walls and serves to hold the latter in spaced relation. The bottom of the housing 9 is open in order that the interior of the housing is accessible from below. The upstanding hook 10 of the primary hanger 5 for the most part overlies the housing 9 and is adapted to be applied to the horizontal rod 8, as shown in Figure 1. It embodies a depending or downwardly extending shank 15, the lower end of which extends into the upper central portion of the interior of the housing 9 through a circular hole 16 in the upper central portion of the arcuate side wall 14 of the housing, i. e., the apex or top of the housing. The arms 11 project outwards in opposite directions from the lower corner portions of the housing 9 and are downwardly curved from their inner to their outer ends. They are preferably formed of comparatively stiff or heavy wire and serve, as hereinafter described, to support the shoulder protector 6. The inner ends of the arms 11 fit snugly within notches 17 in the ends of the side wall 14 of the housing 9 and are connected together by an inverted U-shaped loop 18. The latter is disposed within the interior of the housing 9 and surrounds and engages the inner surface of the arcuate side wall 14. It is secured in fixed relation with the housing 9 as the result of being welded to the housing side wall 14. The lower end of the shank 15 of the upstanding hook 10 is welded to the upper central portion of the semicircular loop 18. By reason of the fact that the loop 18, which serves to connect together the arms 11 and also to anchor the hook 10, is welded to the arcuate side wall 14 the arms and hook are in fixed or connected relation with the housing 9. In addition to the parts heretofore mentioned the primary hanger 5 comprises a horizontally extending rivet 19. This rivet extends through circular holes 20 in the central lower portions of the front and rear walls 12 and 13 of the housing 9

and has a twofold purpose in that it serves as a supporting or suspension medium for the conventional or auxiliary hanger 7 and also to hold the lower central portions of the front and rear walls 13 and 14 against outward deflection or distortion. The primary hanger 5 is so proportioned and constructed that when it is suspended from the horizontal rod 8 by way of the hook 10 the arms 11 are in balanced relation, i. e., they are spaced equidistantly from the subjacent floor.

The shoulder protector 6 is adapted in connection with use of the unit to surround and protect the shoulder portion of the garment that is supported by the unit. It comprises a substantially semicircular front panel 21 and a substantially similarly shaped rear panel 22 and these are formed of Pliofilm, cellophane or like flexible material and are arranged so that the straight margins thereof project downwards. The side margins and the outer portions of the upper margins of the front and rear panels 21 and 22 are connected together by stitching 23. The straight bottom margins of the front and rear panels are free with respect to one another in order that the shoulder protector 6 as a whole is open at the bottom. The central portions of the upper margins of the front and rear panels are provided with integral upstanding tongues 24 and these have rounded upper margins and are free in order that the shoulder protector 6 embodies a top opening for accommodating the housing 9 of the primary hanger 5. As best shown in Figure 4, the tongues 24 lap the front and rear walls 12 and 13 of the housing 9 when the shoulder protector 6 is in supported relation with the primary hanger 5. In assembling the unit the primary hanger 5 is shifted upwards into the interior of the shoulder protector and is manipulated so as to bring the housing 9 into a position wherein it extends upwards through the top opening in the protector and also to bring the outwardly and oppositely extending arms 11 into engagement with the stitched together outer portions of the upper margins of the front and rear panels 21 and 22 of the protector. When the primary hanger is so manipulated the hook 10 projects upwards beyond the top opening in the shoulder protector 6 and is capable of being hooked onto the horizontal rod 8 so as to suspend from the latter the assembly of primary hanger and shoulder cover. In order to form an interlocking means or arrangement for preventing upward displacement of the shoulder protector 6 with respect to the primary hanger 5 the central portions of the front and rear walls of the housing 9 are provided with horizontal slits. The portions of said front and rear walls that are disposed above the slits are struck outwards to define outwardly and downwardly extending lips 25 for surrounding and overlying the upper ends of the upstanding tongues 24. In completing assembly of the shoulder protector 6 with respect to the primary hanger 5 the upper ends of the tongues 24 are inserted under the lips 25, as shown in Figure 4 in order so to interlock the protector relatively to the primary hanger that it is prevented from upward displacement with respect to the primary hanger. If it is necessary to replace the shoulder protector it is only necessary first to remove the primary hanger 5 from the horizontal rod 8 and withdraw the shoulder protector 6 from the primary hanger. Withdrawal of the shoulder protector is effected by first withdrawing the tongues from under the

out-struck lips 25 and then sliding the protector upwards away from the primary hanger.

The auxiliary hanger 7 is of conventional or standard design and comprises an arcuate crossbar 26 and an upstanding hook 27. The hook projects upwards from the central portion of the crossbar and has a depending shank which extends through said central portion of the crossbar and is anchored in place. The crossbar 26 of the conventional or auxiliary hanger 7 is adapted to have the shoulder portion of the garment applied to it and the hook 27 of the hanger is adapted, as shown in Figure 1, to be manipulated into hooked relation with the rivet 19 in order to hold the conventional hanger 7 in connected relation with the primary hanger 5. When the hanger 7 is in suspended or hooked relation with the primary hanger the crossbar 26 is located beneath but in close proximity to the arms 11 of the primary hanger and supports the shoulder portion of the garment so that it is disposed within and is housed by the shoulder protector 6. When it is desired to display or use the garment on the conventional or auxiliary hanger 7 the latter is removed by first unhooking the hook 27 from the rivet 19 and then lowering the conventional hanger 7 so as to withdraw it together with the shoulder portion of the garment from the shoulder protector 6. The hook 27 and the rivet 19 serve as a readily detachable connection between the conventional hanger 7 and the primary hanger 5. It is contemplated that in connection with use of the unit the primary hanger and the shoulder protector will at all normal times remain in suspended relation with the horizontal rod 8, and the conventional hanger 7 will be removed from the primary hanger and shoulder protector when the garment is to be used or displayed and will be hooked onto the rivet 19 when it is desired to suspend the garment from the primary hanger and house the shoulder portion thereof within the shoulder protector 6. By employing the primary and conventional hangers as parts of the unit the life of the unit as a whole is materially increased because removal and application of the conventional hanger does not necessitate passage of a hook through the top opening in the shoulder protector. As shown in the drawings the crossbar 26 is curved conformably to the arms 11 of the primary hanger 5. The herein described hanger and protector unit is comparatively simple in design and hence may be manufactured at a low and reasonable cost. It may be handled with facility and is characterized by the fact that it has a comparatively long life.

The invention is not to be understood as restricted to the details set forth since these may be modified within the scope of the appended claims without departing from the spirit and scope of the invention.

Having thus described the invention what I claim as new and desire to secure by Letters Patent is:

1. As a new article of manufacture, a unitary primary hanger adapted in conjunction with a shoulder protector with an open bottom and a top opening and also a conventional hook equipped garment supporting hanger to hang and protect a garment on the conventional hanger and comprising; (1) a longitudinally elongated open bottom housing shaped and constructed to fit within the top opening of the protector and having fixedly connected thereto an element extending transversely across the lower central portion of its interior and adapted to have hooked

onto it the hook of the conventional hanger, (2) a pair of oppositely extending arms projecting outwards from the lower corner portions of the housing and shaped and constructed to support the shoulder protector, and (3) an upstanding hook extending upwards from the upper central portion of the housing and adapted to be hooked onto a support.

2. As a new article of manufacture, a unit adapted in conjunction with a garment supporting auxiliary hanger to hang and protect the garment while it is on said auxiliary hanger and comprising a unitary primary hanger embodying a longitudinally elongated housing provided on one of the sides thereof with an outwardly extending and downwardly facing lip and having means for receiving and supporting the auxiliary hanger, a pair of oppositely extending arms projecting outwards from the lower corners of the housing, and an upstanding hook extending upwards from the upper central portion of the housing and adapted to be hooked onto a support, and a protector embodying flexible front and rear panels with the outer portions of the upper margins thereof connected together, provided with an access opening for the garment and in addition a top opening adjacent the central portions of the upper margins of the front and rear panels, mounted on the primary hanger so that its outer upper portions rest on said arms and the housing of the primary hanger extends through said top opening, and having on the central portion of the upper margin of one of its panels an upwardly projecting tongue fitting within and interlocked with the lip and serving to hold the protector against upward displacement with respect to the primary hanger.

3. As a new article of manufacture, a unit adapted in conjunction with a garment supporting auxiliary hanger to hang and protect the garment while it is on said hanger and comprising a unitary primary hanger embodying a longitudinally elongated housing having on the sides thereof outwardly extending and downwardly facing lips and having means for receiving and supporting said auxiliary hanger, a pair of oppositely extending arms projecting outwards from the lower corner portions of the housing, and an upstanding hook extending upwards from the upper central portion of the housing and adapted to be hooked onto a support, and a protector embodying flexible front and rear panels with the outer portions of the upper margins thereof connected together, provided with an access opening for the garment and in addition a top opening adjacent the central portions of the upper margins of the front and rear panels, mounted on the primary hanger so that its outer upper portions rest on said arms and the housing of the primary hanger extends upwards through said top opening, and having on the central portions of the upper margins of its panels upwardly extending tongues arranged in interlocked relation with the lips and serving to hold the protector against upward displacement with respect to said primary hanger.

4. As a new article of manufacture, a unitary primary hanger adapted in conjunction with a shoulder protector with an open bottom and a top opening and also an auxiliary garment-supporting hanger to hang and protect a garment on the auxiliary hanger and comprising: (1) a longitudinally elongated open bottom housing shaped and constructed to fit within the top opening of the protector, provided with means

for receiving and supporting the auxiliary hanger, and having disposed longitudinally therein and affixed thereto an inverted U-shaped loop; (2) a pair of oppositely extending arms projecting outwards from the lower corner portions of the housing, having the inner ends thereof connected to the ends of the loop, shaped and constructed to fit within the upper outer portions of the shoulder protector, and adapted when the unitary primary hanger is in operative relation with the shoulder protector to support the latter, and (3) an upstanding hook extending upwards from the upper central portion of the housing and adapted to be hooked onto a support.

5. As a new article of manufacture, a unitary primary hanger adapted in conjunction with a shoulder protector with an open bottom and a top opening and also an auxiliary garment-supporting hanger to hang and protect a garment on the auxiliary hanger and comprising: (1) a 15 longitudinally elongated, comparatively thin, open bottom housing shaped to fit within the top opening of the protector, provided with means for receiving and supporting the auxiliary hanger, embodying notches in its lower corner portions and a vertically extending opening in its top central portion, and having disposed longitudinally therein and affixed thereto an inverted U-shaped loop, (2) a pair of oppositely extending arms projecting outwards from the lower corner 20

10 portions of the housing, having the inner ends thereof fitting within the notches and connected to the ends of the loop, shaped and constructed to fit within the upper outer portions of the shoulder protector, and adapted when the unitary primary hanger is in operative relation with the shoulder protector to support the latter, and (3) an upstanding hook extending upwards from the upper central portion of the housing, adapted to be hooked onto a support, and having the lower end thereof extending through the aforesaid opening in the top central portion of the housing and connected to the central portion of said loop.
